United States Patent Office

Des. 192,289
Patented Feb. 27, 1962

192,289

ELECTRIC CAN OPENER

Michael J. La Forte, Park Ridge, Ill., assignor to Vaughan
Mfg. Co., Chicago, Ill., a corporation of Illinois

Filed July 3, 1961, Ser. No. 65,788

Term of patent 14 years

(Cl. D22—2)

FIG. 1

FIG. 3

FIG. 1 is a perspective view of an electric can opener embodying my invention;

FIG. 2 is a front elevational view thereof;

FIG. 3 is a top plan view thereof; and

FIG. 4 is a side elevational view looking at the right side of FIG. 2.

I claim:

The ornamental design of an electric can opener, substantially as shown.
